UNITED STATES PATENT OFFICE.

OTTO F. FOGELSTRAND, OF KENSINGTON, CONNECTICUT, ASSIGNOR TO
HART MANUFACTURING COMPANY, OF SAME PLACE.

DESIGN FOR COAT AND HAT HOOK.

Specification forming part of Design No. **6,163**, dated October 8, 1872.

To all whom it may concern:

Be it known that I, OTTO F. FOGELSTRAND, of Kensington, in the county of Hartford and State of Connecticut, have invented a Design for a Coat and Hat Hook, of which the following is a specification:

The nature of my design is fully represented in the accompanying engraving, to which reference is made.

The hook consists of three prongs, the ends of which are in imitation of acorns, and the bodies thereof are plain and round. Between

the screw-holes at the front of the base is a raised ornamental figure, which is fully shown in the drawing.

I claim as my invention—

The design for the ornamental figure between the screw-holes and at the base of the several hooks, as shown in the drawing.

OTTO F. FOGELSTRAND.
